United States Patent Office.

JETHRO W. WARNER, OF DOVER, NEW HAMPSHIRE.

Letters Patent No. 96,061, dated October 19, 1869.

IMPROVEMENT IN LASTING-HAMMER.

The Schedule referred to in these Letters Patent and making part of the same.

To all to whom these presents shall come:

Be it known that I, JETHRO W. WARNER, of Dover, in the county of Strafford, and State of New Hampshire, have made an invention of a new and useful Implement to be Employed in Making Boots and Shoes; and do hereby declare the following to be a full, clear, and exact description thereof, due reference being had to the accompanying drawings, making part of this specification, and in which—

Figure 1 is a side representation, and

Figure 2, a longitudinal section of an implement embodying my invention.

The object of this invention is to combine in one instrument, for obvious reasons of convenience, and economy in time and expense, several devices which have heretofore been employed as independent implements in the making of boots and shoes.

The characteristic feature of this invention is the adaptation of a hammer, an awl, and a "spacing-wheel," and such object is accomplished by converting the claw or "pene" portion of the hammer-head into a chuck for holding an awl, and in affixing to the unencumbered end of the handle a spacing-wheel for indenting the sole of a boot for indicating the nail-holes to be punched.

The drawings accompanying this specification represent a shoemaker's hammer, the head of which is shown at *a*, and the handle at *b*.

The striking-face of the hammer-head is denoted by the letter *c*, and its "pene" end at *d*.

In carrying out my invention, I curtail the "pene" end of the hammer-head, as shown in the drawings, and form upon an offset thereto a chuck, *e*, of any suitable construction for holding a stout awl, such as is now universally used in lasting boots and shoes.

Furthermore, in continuance of my invention, I affix to the unencumbered end of the hammer-handle a metallic shank, *f*, carrying an adjustable spacing-wheel, *g*, the outer extremity of the shank serving as a gauge, to bear against the outer edge of the sole, in manner as will readily be understood by boot and shoemakers.

An implement made as above described will be found to answer the purposes of three separate instruments, and will at once recommend itself to boot and shoe-manufacturers.

What I claim as my invention, and desire to secure by Letters Patent, is—

A lasting-hammer, provided at one end with an awl or awl-chuck, and at the other with a spacing-wheel, as herein shown and described.

JETHRO W. WARNER.
